(57) **CLAIM**

The ornamental design for a model vehicle body, as shown and described.

DESCRIPTION

FIG. 1 is a perspective view from above, to the front and to one side of the new design for a model vehicle body; FIG. 2 is a perspective view from above, to the rear and to one side thereof;

FIG. 3 is a top view thereof;

FIG. 4 is a left side view thereof;

FIG. 5 is a right side view thereof;

FIG. 6 is a front view thereof; and,

FIG. 7 is a rear view thereof.

The broken lines immediately adjacent the shaded areas represent the bounds of the claim and all other broken lines represent unclaimed portions of the model vehicle body. None of the broken lines form a part of the claimed design.

1 Claim, 7 Drawing Sheets

FIG. 1

FIG. 2

FIG. 3

FIG. 4

FIG. 5FIG. 6

FIG. 7
